US00D347018S

United States Patent [19]

Jehn

[11] Patent Number: Des. 347,018
[45] Date of Patent: ** May 17, 1994

[54] LASER SIGHT

[76] Inventor: E. F. Jehn, 10F, No. 185, Yung Chi Road, Taipei, Taiwan
[**] Term: 14 Years
[21] Appl. No.: 948,964
[22] Filed: Sep. 16, 1992
[52] U.S. Cl. D16/132
[58] Field of Search ..... 33/241, 243-246, 33/252, 257, 259, 261, 265, 297; 42/100; 356/150-151, 153, 247-250; 359/399, 400, 417-418, 427-429; 250/214 UT, 330; D16/130-136; D22/109-110

[57] CLAIM

A new original design for laser sight, as shown and described herein.

DESCRIPTION

FIG. 1 is a perspective view thereof;
FIG. 2 is a left side view thereof;
FIG. 3 is a right side thereof;
FIG. 4 is a front view thereof;
FIG. 5 is a rear view thereof;
FIG. 6 is a top view thereof;
FIG. 7 is a bottom view thereof; and,
FIG. 8 is a perspective view thereof, the broken lines are for illustrative purposes only and form no part of the claimed design.

FIG. 1

FIG. 2

FIG. 3

FIG. 4

FIG. 5

FIG. 6

FIG. 7
